(57) **CLAIM**

I claim the ornamental design for a survey rover unit using real-time kinematic technology, as shown and described.

DESCRIPTION

FIG. 1 is an upper right front perspective view of a survey rover unit using real-time kinematic technology showing my new design, features shown in broken line are for illustrative purposes only and form no part of the claimed design. The survey rover unit is shown in segments and is depicted with a bracket to disclose an indeterminate length.

FIG. 2 is a lower left rear perspective view thereof. The survey rover unit using real-time kinematic technology is shown in segments and is depicted with a bracket to disclose an indeterminate length.

FIG. 3 is a top plan view thereof.

FIG. 4 is a side elevational view thereof, all four sides are identical thereto. The survey rover unit using real-time kinematic technology is shown in segments and is depicted with a bracket to disclose an indeterminate length; and,

FIG. 5 is a bottom plan view thereof.
